UNITED STATES PATENT OFFICE

ROBERT T. BAILEY, OF PORTLAND, OREGON

CABLE MONKEY

Application filed February 4, 1930. Serial No. 425,843.

Cable monkeys are used for moving heavy or bulky articles vertically and horizontally. One end of the cable is made fast to a beam or other support, and the other end commonly hangs free.

The object of my invention is to provide a cable monkey with driving gear, cable holding drums, slack adjusting means, and means for stopping and holding the load on the cable; and with this and other objects in view my invention consists of the parts and combination of parts hereinafter pointed out.

In the drawings:

Figure 1 is a front elevation of my improved cable monkey.

Figure 2 is a top plan view of the same.

Figure 3 is a vertical sectional view of Figure 2 on the line 3—3.

Figure 4 is a similar view on the line 4—4, Figure 2.

Figure 5 is a vertical sectional view on the line 5—5, Figure 1.

Figure 6 is a detail view.

The reference numeral 6 designates the front plate of the housing, the rear plate being designated by the number 7, the plates being secured to each other by means of the bolts 8.

Shafts 9, 10, 11, 12, are mounted in said housing. On shafts 11 and 12 are fixedly secured the cable winding drums 13, 14, while the slack controlling drums 15 and 16 are secured to the shafts 9 and 10, the drums 13 and 14 being provided with flanges 17. On the shafts 9 and 10 I secure toothed gear wheels 18, 19, and on the shafts 11 and 12, I secure similar gear wheels 20, 21, the gear wheels 20 and 18 intermeshing, while the gears 19 and 21 also intermesh.

A shaft 22 is journaled in the housing and has keyed on it a pinion 23 which intermeshes with gears 18 and 21, said shaft 22 being provided with a crank 24a.

The shafts 9 and 10 are each provided with slack adjusters 24, which are operated by the screws 25. The periphery of the slack drums 15 and 16 is provided with a friction element, such, for instance, as a tire of rubber 26, the purpose of which is to hold the cable 27 in contact position against the drums 13 and 14.

Pawl 28 and 29 are pivoted on the inner face of the plate 6 of the housing and are adapted for engagement with ratchets secured to the gears 20 and 21 of the cable drums 13 and 14. A manually operated rod 30 movably mounted outside of the housing is provided at each end with an elongated slot 31 and 32 adapted to receive pins 33 which limit the throw of the rod. The pawl 28 is pivoted to the housing and is pivotally connected to the upper end portion of the rod as at 34, while the pawl 29 is pivoted at its outer end to the lower end of the rod 30, as at 35, the pawl being pivoted to the housing at 36 intermediate its ends so that with the pawls in engaging position shown in Figures 1 and 4 an upward movement of the rod 30 will disengage the pawls 28 and 29 from the gears 13 and 14. The housing is provided with lifting cables 37 adapted for engaging the load 38, said cables having hooks 39 adapted to engage the lower bolts 8 of the housing.

The upper end of the cable 27 is secured to a support 40.

The load carrying cable 27 hangs loose below the cable monkey housing, but if desired the lower end of this cable may be attached to the housing. The cable is wound the desired number of times to the right on the drum 13, and wound the desired number of times to the left on the drum 14, as shown in Figure 3. The number of windings of the cable on its drums 13 and 14 is dependent on the load to be carried.

With the load secured to the housing the crank 24 is revolved, which through the pinion 23 revolves the cable and slack drums, winding the cable around the drums 13 and 14 whereby the housing is pulled and climbs up on the cable, thus lifting the weight 38. When it is desired to hold the load at a given point the pawls 28 and 29 are in engagement with the ratchets of the gears 20 and 21, but if it is desired to lower the load, or let it rest on a support, the bar 30 is manually operated to lift the pawls out of engagement with the gears 20 and 21.

Thus it will be seen that by my invention I have provided drums and gears for moving the load vertically or horizontally; means for

holding the load in any desired position; means for positive action in lifting, lowering, moving, stopping and holding the load; and means for holding the cable in contact with the pulling drums.

In Figure 6 I show one end of the shaft 22 journalled in a bracket A which is secured to the housing plate 6, the gear wheel 23 being on the shaft between the bracket A and the plate 6, so that the shaft is journalled in said bracket and plate.

What I claim is:

1. In combination, in a cable monkey, a vertically movable frame, horizontal shafts 15 in said frame, a hoisting cable, drums for moving a load, said drums being mounted on said horizontal shafts, means for holding the drums in a desired position, means for positive action on the drums in lifting, lowering, 20 moving, stopping and holding a load, and means for holding said cable in contact with said drums.

2. In combination, in a cable monkey, a vertically movable frame, pairs of horizontal 25 shafts in said frame, diagonally disposed cable winding drums mounted on one pair of said horizontal shafts, diagonally disposed slack drums mounted on another pair of said horizontal shafts in the frame for holding a 30 cable against said winding drums, and means to propel all of said drums.

3. In combination, in a cable monkey, a vertically movable frame, pairs of horizontal shafts in said frame, a hoisting cable, diagonally disposed cable winding drums, mounted 35 on one pair of said horizontal shafts, diagonally disposed slack drums mounted on another pair of said horizontal shafts for holding said cable against said winding drums, 40 means to propel all of said drums, and means to lock said winding drums against reverse action.

4. In combination, in a cable monkey, a vertically movable frame, pairs of horizontal 45 shafts in said frame, a hoisting cable, diagonally disposed cable winding drums, mounted on one pair of said horizontal shafts, diagonally disposed slack drums mounted on another pair of said horizontal shafts for holding 50 said cable against said winding drums, means to propel all of said drums, and means to lock said winding drums against reverse action, or to release said winding drums for reverse action.

5. In combination, in a cable monkey, a vertically movable housing, horizontal shafts in said housing, a hoisting cable, cable winding drums and cable slack drums for holding the cable against said winding drums, said 60 drums being mounted on said horizontal shafts, means to releasably hold the winding drums against reverse movement, and means to propel said drums.

6. In combination, in a cable monkey, a 65 housing, diagonally disposed cable winding

drums, diagonally disposed slack drums for holding a cable against said winding drums, means to propel said drums, a catch engaging each of the winding drums, and common means to release said catches from engagement with the winding drums.

7. In combination, in a cable monkey, a housing, cable winding drums diagonally disposed in said housing, cable slack drums diagonally disposed in said housing, gears associated with said drums, pawls engaging the gears of the winding drums, a common means for moving said pawls to disengaged position, and means for driving said drums.

8. In combination, in a cable monkey, a housing, cable winding drums diagonally disposed in said housing, a cable wound in opposite directions on the respective winding drums, slack drums for holding the cable against the winding drums and diagonally disposed in said housing, gears to drive said drums, means for driving said gears, pawls engaging the gears of the winding drums, a common means for moving said pawls to inoperative position, and means for driving said gears.

9. In combination, in a cable monkey, a housing, pairs of horizontal transverse shafts in said housing, diagonally disposed cable winding drums journalled on one pair of said horizontal transverse shafts, diagonally disposed slack drums for holding a cable against said winding drums journalled on another pair of said horizontal transverse shafts, means for propelling the drums, and means for locking the drums against rotation and releasing them for rotation.

In testimony whereof I affix my signature.

ROBERT T. BAILEY.
